UNITED STATES PATENT OFFICE.

HOWARD A. THOMPSON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 11, 1926. Serial No. 128,593.

My invention relates to railway traffic controlling apparatus, and particularly to apparatus of the type wherein governing mechanism on a train is controlled by energy received from the trackway. More particularly the present invention relates to the trackway portion of such apparatus. One feature of my invention is the provision of means for supplying train governing or 10 cab signaling current and track circuit current to a block which is divided into two sections for highway crossing signal purposes.

I will describe one form of apparatus embodying my invention, and will then point 15 out the novel features thereof in claims.

The accompanying drawing is a diagrammatic view showing one form of apparatus embodying my invention.

Referring to the drawing, the reference 20 characters 1 and 1^a designate the track rails of a railway track along which traffic normally moves in the direction indicated by the arrow. These rails are divided by insulated joints 2 to form a block C—E, and this block is further divided by similar joints 2 into a rear track section C—D and a forward track section D—E. Located adjacent the point D is a highway crossing signal H, which may be of any suitable form 25 and which, as here shown, is an electric bell.

The forward track section D—E is provided with a track circuit comprising a transformer T^E and a track relay R^E. The secondary 20 of transformer T^E is constantly 30 connected across the rails at the exit end of the section, a limiting reactance 44 being interposed between the secondary and one track rail in the usual manner. The primary 19 of transformer T^E is constantly supplied with alternating current of one 35 relative polarity or the other according as the track relay R^E for the section next in advance is energized or de-energized. When relay R^E is energized, the circuit is from one 40 terminal A of a source of alternating current, through front contact 5, wires 7 and 9, primary 19, wires 10 and 8, and front contact 6 to terminal B of the same source of 45 alternating current. When relay R^E is de-energized, the circuit is the same, except that the relative polarity of the current in winding 19 is reversed due to the pole-changing action of contacts 5 and 6 of relay R^E. Track relay R^E has two windings 3

and 4, the former of which is connected 55 across the rails adjacent the entrance end of section D—E. Winding 4 is supplied with alternating current from the same source as that from which primary 19 of transformer T^E is supplied. That is to say, 60 the wires 11 and 12 leading to winding 4 are connected respectively with wires 7 and 8, so that winding 4 is supplied with alternating current of one relative polarity or the other according as track relay R^E is energized or de-energized. It follows that track relay R^E is always energized when section 65 D—E is unoccupied, and that the reversal of the relative polarity of the current in primary 19 of transformer T^E has no effect on 70 the track circuit because a simultaneous reversal of relative polarity occurs in winding 4 of relay R^E.

Referring now to section C—D, the normal track circuit for this section comprises a 75 transformer T^D, the secondary 20 of which is connected across the rails adjacent the exit end of the section, and a track relay R^D having a winding 3 connected across the rails adjacent the entrance end of the section. 80 Primary 19 of transformer T^D and the second winding 4 of relay R^D are supplied with alternating current in multiple from the same source as that which supplies current to the track circuit for section D—E. That 85 is to say, the primary circuit for transformer T^D is from wire 11, through wire 13, front contact 15 of track relay R^D, wire 17, primary winding 19 of transformer T^D, wire 18, front contact 16 of relay R^D, and wire 14 to 90 wire 12. The multiple path including winding 4 of relay R^D is from wire 17, through wire 21, wire 45, front contact 31 of a relay F, wire 47, winding 4, wire 48, front contact 32 of relay F, and wires 46 and 22 to wire 18. 95 It will be noted that the supply of current from the source at point E to winding 19 of transformer T^D and to winding 4 of track relay R^D will be discontinued when track relay R^D is de-energized. If relay F is de-energized, however, winding 4 becomes energized from a source of current located at point C, the circuit being from terminal A of such source through back contact 31 of relay F, wire 47, winding 4, wire 48, and 100 back contact 32 to the terminal B.

An auxiliary track relay R^x is connected across the rails at the exit end of section

C—D through a reactance 43 which is shunted by back contact 49 of track relay R^p when the latter relay is de-energized. An auxiliary track transformer T^x has its secondary 20 connected across the rails adjacent the entrance end of section C—D through a limiting reactance 44, but the primary 19 of this transformer is normally de-energized. When relay F is de-energized, the primary circuit 25 for transformer T^x is closed, this circuit being from terminal A, through back contact 50 of relay F, and the primary 19 of transformer T^x to terminal B.

Relay F is connected in multiple with the 30 primary 19 of the normal track transformer T^p, that is, the winding of this relay is connected across wires 21 and 22 by means of wires 29 and 30. It follows that relay F is energized or de-energized according as track 35 relay R^p is energized or de-energized, that is, according as section D—E is unoccupied or occupied.

Located at the point C is a signal relay K^c having two windings 25 and 26. Winding 25 is constantly supplied with alternating current from the two terminals A and B, while winding 26 is connected in multiple with the winding of relay F. That is to say, winding 25 is connected across wires 21 and 22 by means of wires 23 and 24. It follows that relay K^c is energized in one direction or the other according as track relay R^p is energized or de-energized, and that relay K^c is de-energized when relay R^p is de-energized.

Located adjacent the entrance end of section C—D is a signal S^c, which as here shown, is of the electric lamp type, comprising a proceed lamp G, a caution lamp Y, and 40 a stop lamp R. These lamps are controlled by contact 37 of track relay R^c and by contact 27 of signal relay K^c, through circuits which will be obvious from the drawing and which have nothing to do with my present invention. A similar signal S^e is located at the entrance end of the section to the right of point E, and is similarly controlled by a track relay R^e and signal relay K^e.

The supply of current to the primary 19 of transformer T^c for the section to the left of point C, is as follows:

When track relay R^c and line relay F are both energized, current flows from terminal A, through front contact 33 of relay F, front contact 39 of relay R^c, primary 19, front contact 38 of relay R^c, and front contact 34 of relay F to terminal B. When track relay R^c is de-energized, current flows from terminal A, through back contact 38 of relay R^c, primary 19, and back contact 39 of relay R^c to terminal B. When relay F is de-energized, current flows from terminal A, through back contact 33, primary 19 and back contact 34 to terminal B.

The crossing bell H is controlled jointly

by back contact 35 of track relay R^c and back contact 36 of track relay R^x, so that when either or both of these relays is de-energized, the crossing bell will be in operation, but that when both of these relays are energized 70 the bell will be silent.

The apparatus shown herein is intended for co-operation with train-carried governing mechanism responsive to the presence of track circuit current in the track rails, so 75 that in order to permit a train traveling at full speed a source of track circuit current must be connected across the rails in advance of the train.

The operation of the apparatus is as follows: When there is no train in either section C—D or the section next to the right, all track relays are energized, line relay F is energized, and signal relay K^c is energized in normal direction so that signal S^c 80 indicates proceed. A train entering section C—D will receive track circuit energy from transformer T^p, so that the train is free to proceed at full speed through the section. As soon as the train enters section C—D, track relay R^c will become de-energized and contact 35 of this relay will, of course, set the crossing bell H into operation. Track circuit current of reverse relative polarity will then be supplied to transformer T^c, through back contacts 38 and 39 of track relay R^c. Relay F, however, will remain energized. As the train approaches the exit end of section C—D, it will de-energize the auxiliary track relay R^x, but this will have no effect on the rest of the apparatus.

When the forward end of the train enters section D—E, it will de-energize track relay R^p, thereby opening at contacts 15 and 16 the primary circuit for transformer T^p, the 90 circuit for relay F, and the circuit for winding 25 of relay K^c. Relay F will, therefore, become de-energized and so will close at contact 50 the primary circuit for transformer T^x, with the result that track circuit 95 current will be supplied to the rails at the entrance end of section C—D. The opening of relay F will open the circuit for winding 4 of track relay R^c at contacts 31 and 32, but this winding will immediately become 100 energized through the back contacts 31 and 32 of relay F, with the result that relay R^d will become energized from the current supplied by the auxiliary track transformers T^x. When the rear of the train leaves section 105 C—D, the auxiliary track relay R^x will become energized by the current supplied from transformer T^x, and so the operation of the crossing bell H will be discontinued. With a train in section C—D, the track circuit 110 for section C—D includes a transformer at the entrance end of the section and a track relay at the exit end of the section, so that a second train entering section C—D will 115 not receive track circuit current and such 120

125

second train will, therefore, receive a stop indication. When the first train passes out of section D—E and into the section next to the right, track relay R^D will become energized and signal relay K^c will also become

energized, but the current supplied to winding 25 of this relay will be of reverse relative polarity, because track relay R^E is now de-energized; caution lamp Y of signal S^c will, therefore, become lighted. Relay F will become energized, thereby discontinuing the supply of current to the primary of transformer T^x , but the primary of transformer T^D is now energized from the source

15 at point E, so that track relay R^c will remain energized. A following train entering section C—B will, therefore, receive track circuit energy from transformer T^D at the exit end of the section. Of course, when 20 the first train is in the forward section D—E, so that line relay F is de-energized, track circuit current of reverse relative polarity is supplied to the primary of track transformer T^c , through back contacts 33 and 25 34 of this relay, but when this relay becomes energized, due to the train leaving section D—E, the normal supply of current to the primary of transformer T^c is restored.

The reactance 42 in series with winding 30 of track relay R^c is shunted by contact 28 of signal relay K^c and is provided in order to avoid over-energization of this winding while the winding is receiving energy from the auxiliary track transformer T^x , similarly, the reactance 43 in series with the winding 35 of relay R^x is shunted by back contact 49 of track relay R^D and is provided to avoid over-energization of this winding when it is receiving energy from track transformer T^D .

40 Although I have herein shown and described only one form of apparatus embodying my invention, it is understood that various changes and modifications may be made therein within the scope of the appended 45 claims without departing from the spirit and scope of my invention.

Having thus described my invention, what I claim is:

1. In combination, a block of railway 50 track divided into a rear and a forward section, two sources of track circuit current for said rear section located at the entrance and the exit ends of the section respectively, and means for supplying current to the rear 55 section from one or the other of said sources according as the forward section is occupied or unoccupied.

2. In combination, a block of railway 60 track divided into a rear and a forward section, two sources of track circuit current for said rear section located at the entrance and the exit ends of the section respectively, and means for supplying current from the source at the entrance end but not from the 65 other source when the forward section is oc-

cupied and from the source at the exit end but not from the other source when the forward section is unoccupied.

3. In combination, a block of railway 70 track divided into a rear and a forward section, two sources of track circuit current for said rear section located at the entrance and the exit ends of the section respectively, two track relays located at the entrance and the exit ends respectively of said rear section, 75 the relay at the exit end being responsive to current from either source, a highway crossing signal located adjacent the junction of said two sections and controlled by said two relays, and means for supplying current to 80 the rear section from one or the other of said sources according as the forward section is occupied or unoccupied.

4. In combination, a block of railway 85 track divided into a rear and a forward section, a main transformer having its secondary connected with the rails at the exit end of the rear section, an auxiliary transformer having its secondary connected with the rails at the entrance end of the rear section, a main track relay having a first winding connected with the rails at the entrance 90 end of the rear section and also having a second winding, an auxiliary track relay connected with the rails at the exit end of 95 the rear section, a line relay for the rear section, means for supplying current to the primary of said main transformer and to said line relay and to the second winding 100 of said main track relay when the forward section is unoccupied but not when it is occupied, means for also supplying current to the second winding of said main track relay and to the primary of said auxiliary transformer when said line relay is de-energized, 105 and a highway crossing signal controlled jointly by said two track relays.

5. In combination, a block of railway 110 track divided into a rear and a forward section, a main transformer having its secondary connected with the rails at the exit end of the rear section, an auxiliary transformer having its secondary connected with the rails at the entrance end of the rear section, a main track relay having a first winding connected with the rails at the entrance 115 end of the rear section and also having a second winding, an auxiliary track relay connected with the rails at the exit end of the rear section, a line relay for the rear section, means for supplying current to the primary of said main transformer and to said line relay and to the second winding of said main track relay when the forward section is unoccupied but not when it is occupied, means 120 for also supplying current to the second winding of said main track relay and to the primary of said auxiliary transformer when said line relay is de-energized, means controlled by said main track relay and by 125 130

said line relay for supplying track circuit current to the rails in the rear of said rear section, and a highway crossing signal controlled jointly by said two track relays.

- 5 6. In combination, a block of railway track divided into a rear and a forward section, means operating when the forward section is unoccupied to supply track circuit current to the rails at the exit end but not
10 at the entrance end of the rear section, means operating when the forward section is oc-

cupied to supply track circuit current to the rails at the entrance end but not at the exit end of the rear section, two track relays located at the two ends of the rear section and each responsive to track circuit current supplied to either end of the section, and a highway crossing signal located adjacent the junction of said sections and controlled jointly by said two track relays. 15 20

In testimony whereof I affix my signature.
HOWARD A. THOMPSON.
